G. W. BAUGHMAN

RAILWAY TRAFFIC CONTROLLING APPARATUS

Filed Oct. 10, 1924

UNITED STATES PATENT OFFICE.

GEORGE W. BAUGHMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 10, 1924. Serial No. 742,841.

To all whom it may concern:

Be it known that I, GEORGE W. BAUGHMAN, a citizen of the United States, residing at Edgewood Borough, in the county of 5 Allegheny and State of Pennsylvania, have invented certain new and useful Improvements in Railway-Traffic-Controlling Apparatus, of which the following is a specification.

10 My invention relates to railway traffic controlling apparatus, and particularly to apparatus of the type comprising train carried governing apparatus controlled by energy received from the trackway. More 15 specifically, my present invention relates to the trackway portion of such apparatus.

I will describe one form of apparatus embodying my invention, and will then point out the novel features thereof in claims.

20 The accompanying drawing is a diagrammatic view showing one form of railway traffic controlling apparatus embodying my invention.

Referring to the drawing, the reference 25 characters 1 and 1^a designate the track rails of a stretch of railway track. These rails are divided, by means of insulated joints 2, into a plurality of track sections, of which only one section, A—B, is shown in the drawing.

Each track section is provided with a 30 source of track circuit current, here shown as a track transformer designated by the reference character T with an exponent corresponding to the location and having a 35 secondary winding 5 connected across the rails adjacent the right hand end of the section. An impedance 6, here shown as a reactor, is interposed between the secondary 40 5 of each track transformer T and one rail 1^a of the associated section. The primary 4 of each track transformer is constantly supplied with alternating current from a suitable source such as an alternator M over 45 line wires 3 and 3^a.

Each section is further provided with a 50 track relay designated by the reference character R with an appropriate exponent and connected across the rails adjacent the left hand end of the associated section. These relays may be used to control traffic governing means not shown in the drawing in any desired manner.

Means are also provided for supplying

section A—B with a loop current which flows 55 through the rails of the section in parallel. For this purpose I connect an impedance 11 across the rails adjacent the left hand end of the section and a similar impedance 12 across the rails adjacent the right hand end of the 60 section. As here shown the opposition offered by impedances 11 and 12 is largely due to their ohmic resistance. The immediate source of loop current for this section is a loop transformer L having the terminals of its secondary 65 9 connected with the mid points of impedances 11 and 12. The primary 8 of transformer L is supplied with alternating current from line wires 3 and 3^a, over a front contact 7 of track relay R^B. It follows that 70 when relay R^B is energized, that is, when the section to the right of point B is unoccupied, section A—B is supplied with loop current.

The section to the left of point A is occupied by a train indicated diagrammatically at V. Located in front of the forward axle of this train are two magnetizable cores 16 and 16^a provided with windings 17 and 17^a, respectively, and one located in inductive relation with each track rail. Windings 17 and 17^a are connected in series in such manner that the voltages induced therein by alternating currents flowing in opposite directions in the two track rails at an instant 85 are additive. The two windings 17 and 17^a deliver current to winding 18 of an induction motor relay K. Located at some other convenient place on the train, such as in rear of the first axle, are two other cores 90 19 and 19^a carrying windings 20 and 20^a respectively and one located in inductive relation with each track rail. The two windings 20 and 20^a are connected in series in such manner that voltages induced therein 95 by alternating currents flowing in the same direction in the two track rails at an instant are additive and these windings serve to supply current to winding 21 of relay K. Suitable amplifying apparatus 25 may be 100 interposed between each winding of relay K and the receiving apparatus on the train.

In addition to the two windings 21 and 18, relay K comprises a rotor 22 and a contact system comprising a contact 23 controlled thereby. This relay may be used to control train governing apparatus not shown in the drawing, in any desired manner. When

the train V occupies a stretch of track which is supplied with track circuit current, winding 18 of relay K is energized, and should this stretch of track be supplied also with 5 loop current, winding 21 would be energized and the relay would be operated. Relays similar to K customarily have an optimum phase relation between the currents in the two windings at which the torque exerted 10 by the relay is a maximum for a given value of the currents in the relay. I shall here assume that relay K is of such construction that this optimum phase relation is 90°. The torque of a relay of this type increases with 15 increases in the sine of the phase angle and also, of course, with increases in the current through either winding.

It will be seen that the track circuit current traverses a reactor 6 whereas the loop 20 current traverses resistances 11 and 12 which are substantially non-inductive, and as a result the loop current and the track circuit currents would ordinarily be displaced in phase substantially 90°.

25 I have found, however, that in long track sections a portion of the loop current leaks away from the rails at one end of the section, traverses the ground instead of the rails, and returns to the rails at the other end of the section. As a result the magnitude of the loop current near the center of the section is considerably smaller than adjacent the ends of the section, and, moreover, the loop current near the center of the 30 section lags behind the loop circuit voltage by a considerable amount. The phase angle between the loop and track circuit currents is therefore diminished and the operation of the relay K is rendered less reliable.

40 To overcome this undesirable condition I connect an impedance comprising two reactors 10 and 10^a in series across the rails adjacent the left hand end of the section and connect the left hand terminal of primary 8 of loop transformer L with the common point d of these reactors. I also connect the right hand terminals of primary 8 and secondary 9 together. By properly proportioning the reactors 10 and 10^a the loop 45 current may be made to lead the loop voltage and thereby to counteract the lag caused by leakage through the ground.

50 The parts are so proportioned that the optimum phase relation between the loop and track circuit currents is obtained near the center of the section. At the ends of the section, then, the loop current will lead the applied voltage, and the track circuit current will lag behind the applied voltage 55 by approximately 90°. The phase angle will, then, at the ends of the section, be less desirable than the optimum, but at the ends of the track section the loss due to leakage through ground is a minimum and the magnitude of the current in the rails at those

points is sufficient to insure reliable operation of the relay.

It follows that with my invention the operation of the relay is more reliable, and that safety of operation may be insured 70 with less power, than would be the case were the loop current not shifted to lead the voltage.

75 Although I have herein shown and described only one form of railway traffic controlling apparatus embodying my invention, it is understood that various changes and modifications may be made therein within the scope of the appended claims without departing from the spirit and scope 80 of my invention.

Having thus described my invention, what I claim is:

1. In combination, a stretch of railway 85 track, a transformer, a loop circuit including the rails of the stretch in parallel and the secondary of said transformer, means for supplying energy to the primary of said transformer, and means for connecting one terminal of said primary with one terminal 90 of the secondary and for connecting the remaining terminal of said primary with the rails of said stretch.

2. In combination, a stretch of railway track, a transformer having a primary and 95 a secondary, means for supplying said primary with alternating current, and means for supplying current to the rails of the stretch in parallel from said primary and from said secondary.

100 3. In combination, a stretch of railway track, a transformer having a primary and a secondary winding, means for connecting one terminal of each of said winding with the rails of the stretch, means including an impedance for connecting the free terminal of said primary winding with the rails, and means including a second impedance having a power factor different from the power factor of said first impedance for connecting the free terminal of the secondary winding with the rails of the stretch.

105 4. In combination, a stretch of railway track, a transformer having a primary and a secondary winding, a first impedance connected across the rails adjacent one end of the stretch, a second and a third impedance connected across the rails adjacent the other end of the stretch, means for connecting one terminal of each winding of said transformer with the said first impedance, and means for connecting the free terminals of said primary and secondary windings with said second and third impedances, respectively.

110 120 125 5. In combination, a section of railway track, a source of alternating electromotive force, means for supplying to the section a track circuit current which lags such electromotive force by substantially 90°, means

for supplying the rails of the section with loop current which leads said electromotive force at the ends of the section, but the magnitude of which loop current is diminished 5 and the lead of which loop current with respect to said electromotive force is decreased near the center of the section, due to leakage of current through the ground, and train carried governing means including a 10 relay having a torque which increases with increase in the magnitude of either track circuit current or loop current and also with increase in sine of the phase angle between said currents.

15 6. In combination, a stretch of railway

track, a transformer having a primary and a secondary, means for supplying the primary with alternating current, means for connecting one terminal of each winding of said transformer with the rails of the stretch, a resistor connected across the rails of the stretch and having its mid point connected with the free terminal of said secondary, and two reactors connected in series 20 across the rails of the stretch and having their common point connected with the free 25 terminal of said primary.

In testimony whereof I affix my signature.

GEORGE W. BAUGHMAN.
